UNITED STATES PATENT OFFICE

105,294

DESIGN FOR A CARBON DIOXIDE ABSORPTION BULB

Charles R. McCabe, Toledo, Ohio

Application April 30, 1937, Serial No. 69,095

Term of patent 14 years

To all whom it may concern:

Be it known that I, Charles R. McCabe, a citizen of the United States and resident of Toledo, in the county of Lucas and State of Ohio, have invented a new, original, and ornamental Design for a Carbon Dioxide Absorption Bulb, of which the following is a specification, reference being had to the accompanying drawing, forming a part thereof.

Fig. 1 is a side view of a carbon dioxide absorption bulb, showing my new design, and Fig. 2 is a top plan view thereof. The entire article is of glass.

I claim:

The ornamental design for a carbon dioxide absorption bulb, substantially as shown and described.

CHARLES R. McCABE.
